United States Patent

Des. 240,333

Patented June 22, 1976

240,333

MONOCULAR

M. Gaines Chesnut, Denver, Colo., assignor to Outdoor Sports Industries, Inc., Denver, Colo.

Filed Nov. 29, 1974, Ser. No. 528,286

Term of patent 14 years

Int. Cl. D16—66

U.S. CL. D16—66

FIG. 1 is a perspective view of the monocular showing my new design;

FIG. 2 is a side elevational view thereof;

FIG. 3 is a bottom plan view thereof;

FIG. 4 is a top plan view thereof;

FIG. 5 is a side elevational view taken from the side opposite that shown in FIG. 2;

FIG. 6 is an end elevational view thereof taken from one end of the monocular of FIG. 1; and

FIG. 7 is an end elevational view thereof taken from the other end of the monocular of FIG. 1.

I claim:

The ornamental design for a monocular, as shown.
